UNITED STATES PATENT OFFICE.

JAMES D. BERGEN, OF MERIDEN, CONNECTICUT, ASSIGNOR TO THE J. D. BERGEN COMPANY, OF SAME PLACE.

DESIGN FOR A GLASS VESSEL.

SPECIFICATION forming part of Design No. 27,457, dated August 3, 1897.

Application filed June 21, 1897. Serial No. 641,718. Term of patent 3½ years.

To all whom it may concern:

Be it known that I, JAMES D. BERGEN, of Meriden, in the county of New Haven and State of Connecticut, have invented a new 5 Design for Glass Vessels; and I do hereby declare the following, when taken in connection with the accompanying drawings and the letters of reference marked thereon, to be a full, clear, and exact description of the same, 10 and which said drawings constitute part of this specification, and represent, in—

Figure 1, a plan view of the vessel; Fig. 2, a vertical central section thereof.

This invention relates to a design for the 15 ornamentation of glass vessels; and the design consists in the configuration and ornamentation as shown in the accompanying illustrations.

As herein shown, the design consists of a 20 seven-pointed star A, radiating from a smaller central star B, which forms the center of the under side of the vessel. At the apex of each point of the star A its outlining grooves converge, then gradually expand upwardly, then

inwardly, forming an elongated lobe-shaped 25 ornament C, the converging lines at the upper surface of the vessel forming a deep scallop D in the upper configuration thereof. The surface of the lobe-shaped ornament C, as well as the spaces inclosed by the grooves 30 forming the points of the star A, are filled by hatched ornamentation E.

The spaces between the lobe-shaped ornaments are filled with ornate stars F along the upper surface of the vessel, while small fan-like ornaments G fill the spaces between the points of the star A, all as shown in the accompanying illustrations.

I claim—

The design for a glass vessel as herein shown 40 and described.

In testimony whereof I have signed this specification in the presence of two subscribing witnesses.

JAMES D. BERGEN.
